UNITED STATES PATENT OFFICE.

ALBERT A. HUSEBY, OF CHICAGO, ILLINOIS.

COMBINED PHONOGRAPH-CABINET AND PACKING-CASE THEREFOR.

1,333,658.

Specification of Letters Patent. Patented Mar. 16, 1920.

Application filed October 24, 1919. Serial No. 332,870.

To all whom it may concern:

Be it known that I, ALBERT A. HUSEBY, a citizen of the United States, residing at Chicago, in the county of Cook and State 5 of Illinois, have invented certain new and useful Improvements in Combined Phonograph-Cabinets and Packing-Cases Therefor, of which the following is a specification.

In packing and shipping phonograph 10 cabinets, considerable difficulty has heretofore been experienced in packing the cabinets in such a way as to prevent chafing and abrasion of the polished and ornamental exterior surface of the cabinet by the packing 15 case and the filling and supporting elements within the latter that are designed to hold the cabinet against movement within the case. So far as I am aware it has heretofore been the practice to build the case in 20 such a size as to contain the cabinet with slight top and side clearance, and to rely upon filling strips surfaced on their cabinet 25 engaging sides with felt, cloth or like material to support the cabinet against relative movement within the case.

My present invention is designed to provide a cabinet and packing case with means 30 positively and rigidly uniting the two temporarily during shipment so as to prevent any movement of the cabinet within the case and consequent chafing and marring of 35 the cabinet, a further object being to provide a means of this sort of such a character as to not require in its application any dis- 40 figurement of the cabinet or any alteration of its present standard construction.

In order that my invention may be readily understood and practised by those acquainted with packing instrumentalities of 45 this general nature, I have illustrated the same in the accompanying drawings in which—

Figure 1 is a vertical section of a packing case with a phonograph cabinet placed 50 therein, the latter being partly broken out and in section and showing my improved means for rigidly connecting a side of the cabinet to the adjacent side of the packing case; and

Fig. 2 is a rear view of the packing case and cabinet, partly broken away and in vertical section at top and bottom.

Referring to the drawing, 5 designates as 55 an entirety a phonograph cabinet of the conventional upright form at present extensively known and used, and 6 designates as

an entirety a packing case therefor. The lower end of the cabinet is supported upon intersecting bars or rails 7 and 8 in a manner which permits the feet and casters to 60 enter between the rails and be held off the bottom wall of the packing case, the lower end of the cabinet being secured against lateral movement relatively to the case by means such as screws 9 passing through the 65 rails 8 of the case and into the base board 10 of the cabinet.

To the top wall of the cabinet is secured a wooden strip 11 covered on its lower surface with cloth or felt 12 and bearing directly on the top of the lid or covering of the cabinet.

The attachments of the packing case thus far described for engaging with the top and bottom of the cabinet have heretofore 75 been known and practised in the packing and shipping of phonograph cabinets, but alone they have been found altogether inadequate to prevent relative movement of the cabinet within the case during transit 80 and consequent greater or less marring or chafing of the ornamental surface finish of the cabinet.

My present invention takes advantage of the fact that most cabinets of this type are 85 provided with a removable panel in the rear wall of the cabinet, the opening covered by said panel being indicated at 13 in Fig. 1. In accordance with my invention I secure to the two rear legs 14 of the cabinet a 90 stout wooden strip 15 which extends across the upper portion of the opening 13. To the outer side of this strip 15 are secured as by screws 16 a pair of spacing blocks 17 which extend through the opening 13 and at their 95 outer ends abut against the rear wall 6' of the packing case. To and across the back wall 6' of the packing case is secured another stout wooden strip 18, the ends of which are countersunk to bear against the 100 corner frame members 6^a of the case, being strongly secured to the latter by screws 19, while the intermediate portion of the strip or bar 18 bears against the inner back wall 6' of the case directly opposite of the outer 105 ends of the blocks 17. Through the bar 18 and the blocks 17 are inserted long screws 20, which preferably enter the inner strip or cleat 15, as shown in Fig. 1. By this means the upper portion of the cabinet is 110 strongly and rigidly united to a wall of the packing case, so that relative movement

between the two under the more or less rough handling which the packing cases receive in shipment is rendered impossible, and the rubbing and marring of the surface of the cabinet heretofore frequently experienced under methods of packing are avoided.

The bar or cleat 15 is built into the cabinet as a permanent element thereof, so that, 10 in removing the cabinet from the case, it is necessary only to withdraw the screws 16 and 20, which frees the bracing blocks 17 and enables the cabinet to be readily withdrawn from the casing. When the rear 15 panel is in place, the presence of the packing strip or cleat is, of course entirely concealed.

I claim—

1. The combination with a cabinet having 20 a panel opening in one side thereof, and a packing case for said cabinet, of means extending through said panel opening and rigidly uniting a side wall of the packing case to an interior portion of said cabinet to prevent relative lateral movement of the cabinet and packing case during transportation.

2. The combination with a cabinet having a panel opening, and a packing case for said cabinet, of an internal cleat secured to the

legs of the cabinet across said panel opening, a block secured to said cleat and extending through said opening and abutting against the adjacent wall of the packing case, and means securing the outer end of said block to said wall of the packing case. 30 35

3. The combination with a cabinet having a panel opening, and a packing case for said cabinet, of an internal cleat secured to the legs of the cabinet across said panel opening, a plurality of blocks secured to said 40 cleat and extending through said opening and abutting against the adjacent wall of the packing case, and securing means passed through said wall and blocks and into said cleat. 45

4. The combination with a cabinet having a panel opening, and a packing case for said cabinet, of an internal cleat secured to the legs of the cabinet across said panel opening, a plurality of blocks secured to said 50 cleat and extending through said opening and abutting against the adjacent wall of the packing case, an external cleat secured to the outer side of said wall opposite said internal cleat, and securing means passed 55 through said external cleat, wall and blocks and into said internal cleat.

ALBERT A. HUSEBY.
